11 Claims. (Cl. 15—568)

This invention relates to certain improvements in scouring pads, in the method of making such pads and to a new paste composition particularly adapted for scouring pads.

Scouring pads which are currently available on the market generally comprise steel wool impregnated with a detergent composition which is capable of foaming during use with water in the cleaning of pots, pans, and the like.

One of the disadvantages of certain present-day scouring pads is that the organic detergent present is soap which is unprotected against water hardness. When such a pad is used in hard water the water-soluble soap in the pad reacts with the salts constituting the hardness and forms water-insoluble soap. This insoluble soap, generally termed curd or scum, not only is ineffective as a detergent, thereby reducing the efficiency of the water-soluble soap by necessitating the use of a greater amount for an efficient washing concentration, but also contributes to other undesirable results by its presence. The water-insoluble soap is formed in situ throughout the steel wool mass of the pad, thereby making its removal extremely difficult if not impossible by the usual washing means. After the pad is dry, the water-insoluble soap may become rancid and in that manner impart an unpleasant odor to the pad. It may also render the pad unsightly by contributing a yellowish cast thereto.

Another disadvantage of present-day steel wool scouring pads is that the detergent composition washes out too quickly, thus resulting in a pad wherein the effective life of the steel wool far exceeds that of the soap.

A further disadvantage of present-day scouring pads is the rapid rate at which the pad becomes useless as a scouring means because of the rusting of the steel wool.

Still another disadvantage of present-day steel wool scouring pads is the unattractive appearance which results from the method by which the steel wool and detergent composition are combined to form the pad.

The present invention makes it possible to overcome all or selected ones of these disadvantages of the present-day scouring pads by providing a scouring pad of novel structure which is advantageous regardless of the detergent composition used therein; by providing a new detergent paste composition which gives to a pad of any structure a longer life and superior performance by reason of its controlled rate of solubility and deterutive and rust-inhibiting properties, but which is particularly advantageous in a pad of the present novel structure; and by providing a method of forming scouring pads wherein the detergent and steel wool are more easily and simply combined to form the pad.

Broadly the invention is concerned with a durable scouring pad of novel structure, preferably containing a new permanently plastic detergent paste-filler and the new paste-filler composition per se.

Thus, in accordance with the present invention, a scouring pad comprises a ribbon of matter scouring wool furled about a permanently plastic detergent paste-filler. In its preferred form, the scouring pad of the present invention comprises a ribbon of matted scouring wool spirally surrounding a detergent paste-filler having certain herein-after defined physical properties. A specific paste composition possessing these physical properties as well as de-

2

sirable foaming and rust-inhibiting characteristics also forms part of the instant invention. Broadly, this composition consists essentially of water-soluble non-soap organic surface-active material and an inorganic alkaline buffer salt. Normally, the surface-active component is a mixture of a water-soluble non-soap organic detergent and a fluid water-soluble non-ionic surface-active plasticizer.

A new method of forming the present scouring pads comprises applying a substantially non-aqueous detergent paste to the surface of a ribbon of scouring wool. More particularly it comprises the steps of applying a suitable plastic detergent paste, as defined herein, to the surface of a ribbon of scouring wool, furling said ribbon until the entire length of said ribbon is completely furled, and pressing the exposed end of said ribbon against the body of the resulting pad. In furling, the strip is folded over repeatedly along its length or rolled with the paste-carrying side interiorly disposed to form a pad or roll of desired size, which may then be flattened or further shaped or stamped, as desired. The surface to which the paste is applied may amount to merely a small portion of one end of one face of the strip, or may comprise one whole face thereof, and of course the strips referred to hereinabove may constitute individual strips or be segments of a much longer strip which is cut into units during processing.

The detergent paste is a crucial element of the instant invention. It is essential to the present novel pads and to their preparation that the detergent paste possess certain physical properties. The paste must be plastic and must remain so permanently, i.e., in storage or until the pad is used. It must be water-soluble so as to dissolve during use. It must not become brittle during the life of the pad so as to break into particulate form during use. Furthermore, it must not be liquid, i.e., a free-flowing liquid, at the time of application or thereafter. The detergent paste must be a plastic deformable mass at room temperature, at the temperature of use, and at the temperature of application to the steel wool. The plastic detergent paste which is applied to the strip of steel wool must be sufficiently deformable at the temperature of application that it spreads easily on the strip of steel wool without, however, running through the mass of wool.

A convenient and recognized means of measuring the consistency of plastic, pasty materials is the American Society for Testing Materials Standard Method of Test for Cone Penetration of Lubricating Grease, A.S.T.M. designation D217-48. It has been found that satisfactory detergent pastes are those which, at the customary temperatures of application and use, i.e., in the range from about 70° F. to 185° F., characteristically show penetrations of about 20 to 200 units (one penetrometer unit equals 0.1 mm.) in the A.S.T.M. D217-48 test (as adopted in 1948). Thus, it has been found that pastes characterized by penetrations of less than about 20 units are too stiff to spread during application and tend to crumble and lose their flexibility on aging or storage in pad form. Those pastes having characteristic penetrations significantly greater than about 200 units are unsatisfactory in that they are too free-flowing and tend to cause the formation of pads sticky to the touch. A paste characterized by the desired penetration may be prepared by proper plasticization of a wide variety of organic detergent materials by a suitable choice of additional ingredients, however, examples of a preferred novel composition will be specifically illustrated below.

According to the present invention a preferred detergent paste composition consists essentially of a solid synthetic detergent selected from the group consisting of non-soap anionic and non-ionic high-foaming synthetic organic detergent combined with an inorganic alkaline buffer salt having a pH in aqueous solution of about 8.5

to 11 and preferably from 9.5 to 10.5, and a fluid, essentially non-volatile water-soluble non-ionic surface active plasticizer. When compounded in the proper proportions, this composition forms pastes which exhibit excellent plasticity, foaming, rinsing, detergent and rust-inhibiting properties in the scouring pads of the present invention.

Those synthetic detergents suitable for use in this novel paste composition are selected from the group consisting of the relatively high-foaming anionic and non-ionic detergents, i.e., those anionic and non-ionic synthetic detergents which generate at least about 150 mm. of foam at 0.1% concentration by weight of the Ross-Miles Pour Foam Test (see Ross and Miles, "Oil and Soap," May 1941, pages 99-102; or see Ross and Miles, U. S. Patent 2,315,983). Suitable anionic detergents are well known and include alkali metal and alkaline earth salts of various organic sulfuric reaction products such as the higher alkyl aryl sulfonates, e.g., the sulfonates of alkylated benzene, toluene, cresol, naphthalene and the like in which the alkyl group contains from about 10 to 18 carbon atoms, for example, sodium pentadecyl benzene sulfonate and sodium tetrapropylene benzene sulfonate; higher fatty alcohol sulfates such as potassium lauryl sulfate and the lithium salt of sulfated alcohols derived from coconut oil by reduction; sulfated higher fatty acid monoglycerides such as the magnesium salt of mono-sulfated glyceryl monomyristate; and the higher fatty acid N-substituted taurates such as sodium N-methyl N-ooleoyl taurate. Suitable non-ionic detergents include the solid water-soluble ethylene oxide condensates of water-insoluble (molecular weight 900 to 2,400) polypropylene glycols (Pluronics), and the higher fatty acid alkanolamides such as lauric mono- and diethanolamide. The synthetic detergent normally constitutes about 5 to 60% and preferably 20 to 40% by weight of the composition. Although it is preferred to use normally solid synthetic detergents, normally liquid high foaming detergents such as the ethylene oxide condensates of alkyl phenols (Igepals), e.g., nonyl phenol condensed with from 6 to 16 mols of ethylene oxide, may also be used in the present pastes provided they are mixed with sufficient buffer salt, starch or similar solid material to absorb the liquid and in essence, convert the detergent to a normally solid form.

While it is preferred that the present novel pastes be free of higher fatty acid soap, some soap may be present if there is also present sufficient non-soap organic detergent to protect it from the harmful effects of hard water on its performance.

Suitable surface active plasticizers comprise liquid or pasty fluid, essentially non-volatile, water soluble or dispersible non-ionic surface active agents. These are low melting materials such as the normally fluid alkyloamides of higher fatty acids containing 10 to 18 carbon atoms, for example, the diethanolamides of oleic or coconut oil fatty acids, and the corresponding fluid glycerol amides, as well as the well-known liquid non-ionic detergents of the ethylene oxide condensate type, e.g., ethylene oxide condensates of fatty acids, and fatty acid amides which typically contain from 10 to 18 carbon atoms in the fatty portion thereof. Other suitable ethylene oxide condensates may be prepared from alkyl phenols containing from 6 to 12 carbon atoms, e.g., nonyl phenol. The foregoing ethylene oxide condensates are normally condensed with from 6 to 16 mols of ethylene oxide. Other suitable plasticizers are the liquid or pasty water-soluble ethylene oxide condensates of water insoluble (molecular weight 900 to 3400) polypropylene glycols (Pluronics). These liquid or pasty surface active plasticizers have been found to depress the rate of solubility of the instant compositions in water, thus extending the life of the present novel pads. The plasticizer also contributes foam and detergency to the paste and may, in some cases, exhibit some corrosion inhibiting properties. The plasticizer is used in an amount sufficient to enable the formation of a uniform mixture of the

buffer and synthetic detergent, and normally constitutes from about 20 to 65% and preferably about 20 to 40% by weight of the total composition. Compositions containing less than about 20% plasticizer often are too hard, do not spread evenly and tend to crumble. The presence of more than about 65% of a fluid plasticizer normally results in the formation of pastes which are too thin and tend to separate.

The inorganic buffer salt is present in an amount sufficient to inhibit rusting of steel wool pads in which the instant paste is employed. Thus, it has been found that about 10 to 65% and preferably 20 to 45% by weight of an alkaline inorganic salt, having a buffered pH in dilute aqueous solution of about 8.5 to 11 and preferably 9.5 to 10.5, enables pads containing the instant novel paste composition to overcome the disadvantage of the rapid rate of rusting of the present-day soap-containing steel wool scouring pads. Examples of suitable buffer salts are alkali metal alkaline buffers such as the alkali metal phosphates, e.g., pentasodium tripolyphosphate, tetrasodium pyrophosphate, trisodium phosphate, as well as sodium carbonate, and borax and mixtures thereof.

In order to prevent any deleterious action of the instant alkaline compositions on household aluminum ware, about 3 to 20% and preferably 5 to 10% by weight of a corrosion inhibitor, such as sodium silicate, may desirably be incorporated in the present scouring paste.

One method of preparation of the present novel paste consists of first mixing the detergent and the plasticizer until a uniform mix is obtained. The silicate is then added and the mixture stirred thoroughly, followed by the addition of the alkali metal phosphate. The resulting mixture is stirred, usually at an elevated temperature such as about 170° F., and when homogeneous is applied while warm to a steel wool carrier.

The carrier is typically a length of steel wool approximately 2 3/4" wide and of sufficient length to weigh about 6 grams. Suitable processes by which the present pads may be prepared are illustrated in the accompanying drawings in which: FIGS. 1-6 illustrate the preparation of the pad by depositing a charge of detergent paste on one end of a strip of steel wool, folding or rolling the steel wool around the paste as a core, and crimping the final pad in a press so as to make a form-retaining pad of pillow-shape in which a narrow strip along each edge is permanently crimped while the center portion remains relatively fluffy.

FIGS. 7 and 8 illustrate the initial steps in the preparation of a pad by depositing thin film paste along one entire face of a strip of steel wool and then rolling the thus formed laminate of paste and steel wool to form a pad in which the paste is uniformly distributed.

FIG. 9 illustrates the preparation of pads by injecting paste into a preformed, loosely rolled pad of steel wool by means of a hollow delivery tube inserted into the core thereof.

Referring now to FIGS. 1-6, a charge of a suitable detergent paste 20 as defined herein is applied to the upper surface 24 of an end portion 22 of a steel wool strip 26. The paste-carrying end 22 of the strip is repeatedly folded over as shown by FIGS. 2, 3 and 4 until the entire length of steel wool is furled. The exposed end 30 is placed against the body of the pad (FIG. 4) and, as shown in FIGS. 5 and 6, the pad is crimped in a press 32, which flattens and compresses the entire pad 34 and crimps a narrow border 36 about its edges, thus enabling the pad to maintain its shape.

Another embodiment of the present process is illustrated in FIGS. 7 and 8. According to this embodiment one surface 50 of a ribbon of steel wool 52 is evenly covered over its entire length with a layer of detergent paste 54 having suitable properties as defined herein. The paste-carrying steel wool is then rolled up lengthwise to form a cylindrical pad (illustrated in FIG. 8) which is suitable for crimping in a press such as that

of FIG. 5. After crimping, the final pad is similar in appearance to that of FIG. 6.

In FIG. 9 a nozzle 80 is injected into the core of a previously formed hollow cylinder of steel wool 82. The nozzle is connected to a supply of a suitable detergent paste as defined herein (not shown) and a charge of the paste is injected through the nozzle into the pad. The nozzle is then withdrawn and the pad is crimped as illustrated in FIG. 5 to produce a pad similar in appearance to that of FIG. 6.

By the term "substantially non-aqueous" it is intended to indicate that the present pastes do not depend on water for their fluidity and do not require drying after application to a steel wool carrier. Thus it is contemplated to compound in the instant pastes, for instance, spray dried organic detergents which although apparently dry and free flowing, may in fact contain on the order of 6-8% and even as high as 10% moisture.

The instant substantially non-aqueous pastes have been found to be considerably superior to aqueous pastes in several respects. For instance, it has been found that aqueous pastes on drying in pads tend to become brittle and powdery whereas the present non-aqueous pastes, being free of volatile solvent, remain soft and plastic even on long storage. Furthermore the instant pastes do not require heating and drying in the course of manufacture, as contrasted to pads which employ aqueous compositions as impregnating agents. The latter must be dried in ovens, and normally a considerable fraction of total production is lost by rusting of these pads during drying.

Having described the present invention in its broader aspects, more detailed examples thereof are now given in order to assist in a better understanding of its various ramifications, it being understood that these are included herein for purposes of illustration rather than limitation.

A preferred formula for a detergent paste according to the present invention, expressed as percentage by weight of the entire composition, and methods of use thereof is as follows:

EXAMPLE I

	Percent
Sodium salt of dodecyl benzene sulfonate (ca. 85% active ingredients and 15% sodium sulfate, roll dried)	28.8
Diethanolamide of coconut oil fatty acids	28.8
Sodium tripolyphosphate	34.4
Sodium metasilicate (ratio of $\text{Na}_2\text{O}:\text{SiO}_2$ of 1:2)	8.0

The pH of a 1% solution of this paste is about 10, and the paste exhibits a characteristic penetration of about 64 units in the A.S.T.M. D217-48 Test at 70° F. The paste is heated to about 170° F., at which temperature its penetration is 83. A designated weight of paste is spread over one entire surface of a 6 gm. strip of steel wool measuring about 2 3/4 inches wide. The strip is then rolled up, paste-carrying face inwards, into a cylindrical coil form which is pressed flat.

After cooling to room temperature in the pad, the paste remains soft and flexible, yet is not fluid and remains in the pad. The pad foams copiously initially and during its long life. The steel wool resists rusting until the paste has been substantially completed washed out by usage, at which time foaming ceases too.

EXAMPLE II

In another embodiment of the invention, a paste consisting of 25 parts of sodium dodecyl benzene sulfonate, 25 parts of the diethanolamide of coconut oil fatty acids, 43 parts of pentasodium tripolyphosphate and 7 parts of sodium metasilicate is employed, however, the entire charge of paste is placed on the first two inches of a steel wool strip 2 3/4 inches wide and of designated weight (e.g. 5 or 7 grams) or length. The area to which the paste has been applied is then folded over consecutively

until a pad measuring 2 3/4" x 2 3/4" is obtained. The free end of the resulting pad is pressed into the body of the pad to prevent unravelling. These "core-loaded" pads have an exceptionally long life, as illustrated in Table II, below.

In order to quantitatively evaluate scouring pad durability a test was developed in which a moistened pad is rubbed reciprocally under a fixed load for 120 strokes on a "tin" surface, e.g. tin coated steel (60 strokes on each side of the pad). The pad is rinsed and left to stand 1 to 2 hours under ambient conditions between successive test periods. It has been observed that signs of rusting frequently develop during this interval, thus permitting multiple testing of pads in a relatively short period of time. After repeated application of this rubbing procedure, e.g., 60 strokes on each side followed by a 1 to 2 hour standing period, the foaming of the pad will cease and concurrently the pad will become so corroded that it will be of no further use. This durability test is an indication of the rate of solubility of the detergent paste under the conditions of the experiment, as it is the paste which contributes foaming and anti-rusting properties to the pad.

In carrying out this durability test on the product of Example II, two series of pads were employed, one series containing 7 grams of steel wool per pad, and the other containing 5 grams of steel wool per pad. All pads were prepared from strips of steel wool 2 3/4 inches wide and about 11 to 13 inches long, depending on the weight of steel wool desired and the density of the strip. These two series were run concurrently in a test of durability, the amount of paste in each pad being varied by 1 gram, starting with 5 grams of paste per pad and running to a maximum of 10 grams per pad. The results are tabulated in terms of the number of strokes occurring according to the above testing procedure before the pads lose their power to foam and to resist rusting.

Table II

7 GRAM STEEL WOOL PADS

Grams/paste/pad:	Durability in strokes
5	2760
6	2880
7	2760
8	2760
9	2760
10	3240

5 GRAM STEEL WOOL PADS

Grams/paste/pad:	Durability in strokes
5	2160
6	2280
7	2640
8	2160
9	2640
10	2640

EXAMPLE III

Durability data are obtained by the test procedure of Example II on pads prepared by spreading 10 grams of a paste consisting of 38.8 parts of sodium dodecyl benzene sulfonate, 28.8 parts of the diethanolamide of coconut oil fatty acids, 34.4 parts of pentasodium tripolyphosphate, 2.6 parts of sodium silicate, and 0.4 part of perfume over one entire face of a steel wool strip 2 3/4 inches wide and of sufficient length to weigh 6 grams and then folding the strip to form a pad 2 3/4 inches by 2 3/4 inches. The pads average 1320 strokes.

For comparison purposes, one of the present-day scouring pads now on the market, which consists of approximately 4.6 grams of steel wool impregnated with 6.5 grams of soap, was also subjected to this durability test. This type of pad averaged 600 strokes to depletion of foam and the occurrence of extensive rusting. Another present-day commercially available scouring pad, which contains approximately 8.2 grams of soap and 7.6 grams of steel

wool, was found to average 960 strokes to depletion of foam and the occurrence of extensive rusting.

From the above durability test data it can easily be seen that applicant's pads of comparable size, both in the amount of steel wool and detergent material used, are far superior to those pads now in commercial use.

terials in such amounts as to interfere substantially with the properties and characteristics possessed by the composition set forth but to permit the presence of other materials in such amounts as not substantially to affect said properties and characteristics adversely.

While the invention has been described in terms of pre-

Example IV

[Paste compositions exhibiting satisfactory performance characteristics in pads prepared according to the procedures of the foregoing examples are tabulated below. All parts are by weight.]

Detergent	33.3(A)	25(A)	25(A)	33.3(A)	25(B)	21.4(A) 21.4(C)	25(A)	28.8(C)	28.8(D)	28.8(E)	10.0(A)
Plasticizer (Diethanolamide of coconut oil fatty acids)	33.3	25		25	33.3	25	28.6	25	28.8	28.8	55.0
Inorganic Salts:

Sodium metasilicate	4.7			17.5	4.7	7	7	8.0	8.0	8.0	8

(A)—Sodium tetrapropylene benzene sulfonate.
(B)—Magnesium tetrapropylene benzene sulfonate.
(C)—Sodium lauryl sulfate, technical grade.
(D)—Sodium salt of sulfated coconut oil monoglyceride.
(E)—Sodium-N-methyl-N-octyl taurate.

Example V

Additional suitable paste compositions are:

	Parts by Weight				
Detergent:					
Sodium tetrapropylene benzene sulfonate	25	25	16.3	28.8	28.8
Pluronic L-44 ¹					
Plasticizer:					
Diethanolamide of coconut oil fatty acids	25	25	16.3	14.4	14.4
Diethanolamide of sperm oil fatty acids				14.4	14.4
Diethanolamide of palmitic acid					
Inorganic Salts:					
Pentasodium tripolyphosphate	38	41	19.5	34.4	34.4
Sodium metasilicate	7	7	4.5	8.0	8.0
Adjuvants:					
Starch			43.4		
Petrolatum		2			
Bentonite	5				

¹ Polypropylene oxide of molecular weight 1001-1200 condensed with ethylene oxide in an amount equal to about 40% by weight of the final polymer.

EXAMPLE VI

Another suitable paste composition is:

	Parts by weight
Sodium tetrapropylene benzene sulfonate	28.8
Nonyl phenol condensed with ethylene oxide to an extent averaging 9.5 ethenoxy groups per molecule	28.8
Pentasodium tripolyphosphate	34.4
Sodium metasilicate	8.0

The nonyl phenol-ethylene oxide condensate may be replaced by an equal amount of Pluronic L-63, a polypropylene oxide of molecular weight 1501-1800 condensed with ethylene oxide in an amount equal to about 30% by weight of the final polymer.

Throughout the above disclosure, reference to steel wool carriers has been made, however, other fibrous carriers such as those made of Saran (polymers and copolymers of vinylidene chloride) may be used although steel wool carriers are preferred. When using plastic carriers an abrasive, such as alumina may be incorporated into the paste to give the desired scouring effect.

Summarizing, the present invention is based upon the discovery of a new scouring pad and a new detergent paste for use in scouring pads comprising a high foaming non-ionic or anionic synthetic detergent, a buffer, and a plasticizer which also depresses the solubility of the paste.

The term "consisting essentially of" as used in the definition of the ingredients present in the composition claimed is intended to exclude the presence of other ma-

further embodiments thereof, it is to be understood that considerable variation from the details herein described might be made without departing from the true scope and spirit of the invention. Accordingly, the invention is to be limited only by the claims set forth hereinafter.

What is claimed is:

1. A durable scouring pad comprising a ribbon of matted metallic wool furled about a substantially non-aqueous permanently plastic synthetic organic detergent paste filler which comprises a non-ionic plasticizing material.

2. A durable scouring pad comprising a ribbon of matted metallic wool furled about a substantially non-aqueous permanently plastic synthetic organic detergent paste filler which comprises a non-ionic plasticizing material, characterized by a penetration of about 20 to 200 units in the A.S.T.M. D217-48 penetration test.

3. A durable scouring pad comprising a ribbon of metallic wool furled about a substantially non-aqueous permanently plastic synthetic organic detergent paste composition consisting essentially of water-soluble surface-active non-soap synthetic organic detergent material, non-ionic plasticizing material, and an inorganic alkaline buffer salt, said paste being characterized by a penetration of about 20 to 200 units in the A.S.T.M. D217-48 penetrometer test.

4. A durable scouring pad comprising a ribbon of matted metallic wool furled about a substantially non-aqueous permanently plastic detergent paste filler consisting essentially of a water-soluble non-soap synthetic organic detergent, an inorganic alkaline buffer salt having a pH in aqueous solution of about 8.5 to 11, and a fluid, essentially non-volatile water-soluble non-ionic surface-active plasticizer, said detergent paste being characterized by a penetration of about 20 to 200 units in the A.S.T.M. D217-48 penetrometer test.

5. A durable scouring pad comprising a ribbon of matted metallic wool furled about a substantially non-aqueous permanently plastic detergent paste filler consisting essentially of about 5 to 60% of a water-soluble non-soap synthetic organic detergent selected from the group consisting of non-soap anionic and non-ionic detergents which generate at least about 150 millimeters of foam at 0.1% concentration by weight in the Ross-Miles pour foam test, about 10 to 65% by weight of an inorganic alkaline buffer salt having a pH in aqueous solution of about 8.5 to 11, and about 20 to 65% by weight of a fluid, essentially non-volatile water-soluble non-ionic surface-active plasticizer, which is an alkylolamide of higher fatty acids of 10 to 18 carbon atoms, said detergent paste being characterized by penetration of about

20 to 200 units in the A.S.T.M. D217-48 penetrometer test.

6. A substantially non-aqueous permanently plastic detergent paste composition adapted for use in steel wool scouring pads consisting essentially of non-cationic water-soluble surface-active synthetic organic detergent material and a non-ionic plasticizer which is a higher fatty acid alkylolamide, said detergent paste being characterized by a penetration of about 20 to 200 units in the A.S.T.M. D217-48 penetrometer test.

7. A substantially non-aqueous permanently plastic detergent paste composition adapted for use in steel wool scouring pads consisting essentially of a non-cationic solid water-soluble non-soap organic detergent selected from the group consisting of non-soap non-ionic and anionic high-foaming synthetic organic detergents, an inorganic alkaline buffer salt having a pH in aqueous solution of about 8.5 to 11, and a fluid essentially non-volatile water-soluble non-ionic surface active plasticizer, said detergent paste being characterized by a penetration of about 20 to 200 units in the A.S.T.M. D217-48 penetrometer test.

8. A substantially non-aqueous permanently plastic detergent paste composition adapted for use in steel wool scouring pads consisting essentially of about 5 to 60% of a non-cationic water-soluble non-soap organic detergent selected from the group consisting of non-soap anionic and non-ionic synthetic detergents which generate at least about 150 millimeters of foam at 0.1% concentration by weight in the Ross-Miles Pour Foam test, about 10 to 65% by weight of an inorganic alkaline buffer salt having a pH in aqueous solution of about 8.5 to 11, and

about 20 to 65% by weight of a fluid, essentially non-volatile water-soluble non-ionic surface active plasticizer.

9. A substantially non-aqueous permanently plastic detergent paste composition consisting essentially of about 5 to 20 to 40% of a water-soluble salt of an alkyl aryl sulfonate, about 20 to 40% of a higher fatty acid-diethanolamide and about 20 to 45% by weight of an inorganic alkaline buffer salt having a pH in aqueous solution of about 8.5 to 11.
10. A detergent paste composition as set forth in claim 9 wherein said alkaline buffer salt is pentasodium tripolyphosphate.
11. A detergent paste composition as set forth in claim 9 which contains about 3 to 20% by weight of sodium silicate.
